[57] CLAIM

The ornamental design for a telecommunications access jack, as shown and described.

DESCRIPTION

FIG. 1 is a rear, top, and right perspective view of the telecommunications access jack showing our new design. FIG. 2 is a rear elevational view of the telecommunications access jack.

FIG. 3 is a front elevational view of the telecommunications access jack.

FIG. 4 is a top view of the telecommunications access jack. FIG. 5 is a right side elevational view of the telecommunications access jack.

FIG. 6 is a left side elevational view of the telecommunications access jack; and,

FIG. 7 is a bottom view of the telecommunications access jack.

The broken lines shown in FIGS. 1, 5, and 7 are for illustrative purposes only and form no part of the claimed design.
